CABINET STRUCTURE

Henri Jacques Marc Lambert, Sevres, and Georges Paul Mongin, Saint-Gratien, France

Continuation of abandoned application Serial No. 760, January 6, 1948. This application February 11, 1953, Serial No. 336,424

Claims priority, application France January 18, 1947

3 Claims. (Cl. 312—292)

The object of the present invention is a method for the rational fitting up of furniture, specially of furniture of the domestic type, such as wall-cupboards, wardrobes, ice-chests, bookcase, etc. The present invention is a continuation of my application Serial No. 760, filed January 6, 1948, now abandoned.

It is well known that pieces of furniture of this variety have a fairly large storing capacity with appropriate means of closing. This is the case, in particular, of cupboards fixed to the floor and usually fitted with large cumbersome doors. Another more up to date arrangement is known, comprising two distinct parts: one component attached to the wall and, below it, another component, known as the block, lying on the floor. The upper part of the block forms the working surface and the cupboard, not as deep as the block, is placed at a higher level than the top of the block and leaves the working surface free. It is understandable that it is essential to be able to open or close the cupboard with the greatest ease without the closing mechanism, in its open position, getting in the user's way.

The present specification solves this problem simply and with taste, whether it be a case of cupboards placed on the floor, cupboards fixed above or near the blocks or plain working or serving surfaces.

The method according to the invention is characterised in that it consists in dividing the enclosed volume available inside the piece of furniture in question into two distinct parts, viz. the first of these than can be called the "spare volume" and that is made use of neither frequently nor regularly and the second of usually smaller size and known as the "working volume" that is used very often. The "spare volume" is fitted with a closing device of some common type whilst the "working volume" is supplied with a special means of closing, hardly or not at all cumbersome when in use and preferably associated in its design with the closing device for the spare volume, the border line between the above volumes being defined as it were, by the closing means.

Furthermore, in its open position, the working volume's closing device in no way obstructs access to another volume as in the case of standard sliding doors.

Indeed, the housewife, and the users have at their disposal two distinct volumes formed by the closing means. The working volume only will be readily accessible and will thus contain those articles which are constantly in use. The "spare volume" will only be resorted to on far rarer occasions and that is why its closing means are of far lesser importance.

Other characteristics follow from the description hereinafter presented with reference to the appended drawings and purely by way of example. In said drawings:

Fig. 1 shows a perspective view of a cupboard designed according to invention for domestic use;

Fig. 2 shows a front elevation of it;

Fig. 3 shows a side elevation of it;

Fig. 4 shows a cross-sectional view along line IV—IV of Figure 2;

2

Fig. 5 shows a plan view thereof; Figs. 6 and 7 show cross-sections along lines VI—VI and VII—VII of Figure 2;

Figs. 8 and 9 show different ways of operating the doors that close the "working volume";

Figs. 10 and 11 show front and side views of a means for mechanical operation of the above mentioned door;

Figs. 12 and 13 show front and cross-sectional views of a means for the electric operation of this door; and

Figs. 14 and 15 show a means for controlling several doors.

According to the example of Figures 1 to 7, the chest according to invention comprises a unit 1 made up into a cupboard or a cabinet with several compartments 2, 2', 2'', and combined with a unit 3, made up of a usual block and including the service or working surface 3'. The cabinet 1 is situated above the surface 3'. Each compartment is closed by a door 4, the lower portion of which is cut away at 5 to give a hatch effect as far as possible.

A shutter as at 6 or a similar sort allows the hatch to be closed.

These hatches as at 5 define the limits of the "working" compartment or "volume" 7, whilst the remaining 25 part of the compartment forms the "spare volume" 8.

Frequent use will be made of the "working volume" and occasional use of the "spare volume." Under these conditions if there is no objection to having large sized doors 4 in the way when put to use because done so 30 only on rare occasions, it is essential that the "working volume" be closed without causing any obstruction, since it will be often operated and is at user's height.

Figures 2 to 7, show how to achieve this result:

In this embodiment, shutter 6 slides for instance in 35 the actual body of door 4. A handle 9, for example, allows the shutter to be operated upwards and downwards. A handle 9' allows the door 4 itself to be opened by swivelling on hinges 38 in the usual way (Figs. 2-3). The door panels are shown at 10 and the 40 grooves in which the shutter 6 slides at 11.

Means for lifting the shutter 6 can obviously be arranged and possibly situated at 12.

According to Figure 8, the shutter is made up of screen 15 wound around a roller 16. Figure 9 shows the 45 case of a shutter made of folding slats 17.

Another example illustrated in Figures 10 and 11 shows shutter 6 carrying, on the one hand, a handle 9 for closing by hand, and on the other hand, a stop 19 engaging the under edge 20 of a lever 21 which is subjected to the action of spring 22. The shutter 6 is connected, for instance, to a spiral spring 24 by a cable 23. To open the "working volume" all that is needed is to rock lever 21 in the direction of arrow b, and this allows the shutter 6 to spring up in the direction of arrow f2. The lifting of shutter 6 can be obtained through any power means, so that the shutter may be driven electrically, by compressed air, or hydraulically. Figures 12 and 13 show the lay out of the electrical means. The shutter is attached at 25 to a wire or a cable wound around pulley 27. On the spindle carrying the pulley 27 is mounted a second pulley 29 around which is wound a cable 30 which supports the core 31 of the electromagnet 32. The working of this arrangement is obvious and so is the manner of obtaining a reduction in speed. It is specified that the operation of shutters of a number of cupboards cabinets can be carried out shutter by shutter or simultaneously. The electrical, compressed air, or other control means easily solve the problem by means of general circuit-breakers or control-valves.

In the method by hand, such a simultaneous operation can be obtained, for example, by the arrangement shown in Figures 14 and 15. In this modification, a spindle 33 carries levers 34, 34', 34'' each of

which operates a shutter. A simple handle 35 may thus operate simultaneously all the levers 34. Spindle 33 drives each lever 34 by means of a lug 36 adapted to move within a slot 37 provided in the hub carrying the lever. Of course, the invention is in no way restricted to the methods of operation described and illustrated, for these are only given by way of examples.

It should be pointed out that the use of the cabinet according to the invention must obviously be considered in combination with a usual kitchen block as shown at 3 in Fig. 1 above which said cabinet is situated.

It must further be observed that the following features are also contained in this new cabinet:

(a) the cabinet is situated at such a height with regard to the operator that its lower part is directly accessible when the user stands before it;

(b) the provision of a vertically hinged door closing the entire volume provided inside the cabinet;

(c) a sliding flap is provided in parallel and adjacent relationship with respect to the door and is adapted to slide while remaining in contact with said latter;

(d) said flap opens and closes an opening provided in the lower part of the door and corresponds to the said lower portion of the cabinet which is directly accessible for the user;

(e) the width of the flap and opening is equal the width of the door.

What we claim is:

1. In a kitchen assembly having the usual kitchen block with an upper working surface, a cabinet having a main body space positioned above said surface at such a height that user's access to said main body space of said cabinet is most facilely achieved through its lowermost portion from the front of said block, a vertically hinged door for closing said space, said door including a frame having vertical sides, a top and a bottom, a panel mounted on and covering and filling said frame, said panel having an aperture at the lower part thereof of substantially the width of the door, a vertically slideable flap combined with said panel and adapted to open and close said aperture, said aperture being the only one provided in said door and corresponding to the total available apertured space in between the inner surfaces of the vertical sides and of the bottom part of said frame, said frame having guiding grooves on said vertical sides, said flap engaging and sliding in said grooves, the horizontal width of said flap being somewhat larger than the width of said apertured space, whereby the maximum possible aperture is obtained for a given frame of the door, thus providing the maximum possible access facilities to the inner lower part of the main body space of the cabinet, the said flap sliding closely adjacent to the front face of said panel and being concealed behind it in open position of said flap, spring means connected to said flap and urging it upwards in the open position, and means for locking and unlocking said flap.

2. A cabinet designed to be arranged on a side wall of a room above a kitchen block with an upper working surface, said cabinet having a main body space adapted to be positioned above said working surface at such a height that user's access to said main body space is most facilely achieved through its lowermost portion from in front of said block, a vertically hinged door for closing said space, said door including a frame having vertical

sides, a top and a bottom, a panel mounted on and covering and filling said frame, said panel having an aperture at the lower part thereof of substantially the width of the door, a vertically slideable flap combined with said panel and adapted to open and close said aperture, said aperture being the only one provided in said door and corresponding to the total available apertured space in between inner surfaces of the vertical sides and of the bottom part of said frame, said frame having guiding grooves on said vertical sides, said flap engaging and sliding in said grooves, the horizontal width of said flap being somewhat larger than the width of said apertured space, whereby the maximum possible aperture is obtained for a given frame of the door, thus providing the maximum possible access facilities to the inner lower part of the main body space of the cabinet, the said flap sliding closely adjacent to the front face of said panel and being concealed behind it in open position of said flap, spring means connected to said flap and urging it upwards in the open position, and means for locking and unlocking the flap.

3. For use in overlying relationship to the upper working surface of a conventional kitchen block, a cabinet having an inner space which is composed of a working volume in its lowermost portion to which frequent access is desired for insertion and removal of frequently required kitchen items used on the block and a spare volume for storage of less frequently needed items located above said working volume and to which access is less frequently required, a vertically hinged outwardly swingable door for closing said space, said door including a frame having vertical sides, a top and a bottom, a panel mounted on and covering and filling said frame, said panel having an aperture at the lower part of said panel in front of said working volume, said frame having guiding grooves in its vertical sides, a vertically slideable flap slidably mounted in said grooves for movement relative to said panel to open and close said aperture, said aperture being the only one provided in said panel and spanning the entire width of the door between the vertical sides of said frame, and said flap having a width in excess of the width of the aperture to fit slidably in the grooves and provide maximum possible access to the working volume of the cabinet space when said flap is slid upwardly in said grooves and thereby avoiding the necessity of swinging said door to an open and obstructing position for the user relative to the working surface of said block, said grooves being located behind the front face of the panel so that the flap may slide closely adjacent to the front face of the panel and be concealed behind it in open position of said flap, spring means connected to said flap and urging it upward into the open position, and means for locking said flap in its closed position and for unlocking said flap to permit said spring means to move said flap to its open position.
